(57) **CLAIM**

The ornamental design for a fence panel, as shown and described.

DESCRIPTION

FIG. 1 is an isometric view of a fence panel, showing a first embodiment of my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a cross-sectional view thereof taken along line 6-6 in FIG. 2.

FIG. 7 is a right side elevational view thereof.

FIG. 8 is a left side elevational view thereof.

FIG. 9 is a cross-sectional view thereof taken along line 9-9 in FIG. 2.

FIG. 10 is a front elevational view of a fence panel, showing another embodiment of my new design comprising horizontal and vertical break lines. The break lines depict the boundaries of the claim. The area between the break lines forms no part of the claimed design. All other views are consistent with FIGS. 3-9.

FIG. 11 is a front elevational view of a fence panel, showing yet another embodiment of my new design, which has a different number of sub-panels; and,

FIGS. 12 and 13 are additional front elevational views of the fence panel of the first embodiment showing different unclaimed portions thereof for context only.

Stippling shown in the drawings is intended to represent the three-dimensional contours of the design, and are not intended to indicate surface decoration. The broken lines in the figures depict portions of the fence panel that form no part of the claimed design.

1 Claim, 8 Drawing Sheets
